(57) **CLAIM**

The ornamental design for a car roof rack cross bar, as shown and described.

DESCRIPTION

FIG. 1 is a front, bottom and right side perspective view of a car roof rack cross bar, showing my new design;

FIG. 2 is a front view thereof;

FIG. 3 is a rear view thereof;

FIG. 4 is a left side view thereof;

FIG. 5 is a right side view thereof;

FIG. 6 is an enlarged plan view of its top surface; and,

FIG. 7 is an enlarged plan view of its underside.

The broken lines in the drawings illustrate the portions of the car roof rack cross bar, which form no part of the claimed design.
